UNITED STATES PATENT OFFICE.

LEVI KITTINGER, OF AKRON, OHIO.

DESIGN FOR A MATCH.

SPECIFICATION forming part of Design No. 18,270, dated April 24, 1888.

Application filed March 26, 1888. Serial No. 268,584. Term of patent 14 years.

To all whom it may concern:

Be it known that I, LEVI KITTINGER, a citizen of the United States, residing at Akron, in the county of Summit and State of Ohio, have 5 invented and produced a new and original Design for Matches, of which the following is a specification, reference being had therein to the accompanying drawings, in which—

Figure 1 is a perspective view of a square 10 or rectangular match; Fig. 2, a perspective view of a cylindrical or round match; and Fig. 3, a plan view of the match shown in Fig. 1, these three views being deemed necessary to illustrate my design.

Heretofore matches have been made of a 15 plain smooth splint or stick without indentations of any kind.

The essential feature of my design consists

in providing the stick A—whether square, as shown in Fig. 1, or round, as in Fig. 2—with 20 two slight notches or depressions B in its opposite sides, these notches being located near the upper or undipped end of the match.

I claim—

The design for a match herein shown and 25 described, consisting in providing the match with two depressions near its upper end, these depressions being upon opposite sides of the match.

In testimony whereof I affix my signature in 30 presence of two witnesses.

LEVI KITTINGER.

Witnesses:

A. H. NOAH,
H. C. WILCOX.
